Primary Examiner — Doris Clark(74) *Attorney, Agent, or Firm* — Buchanan Ingersoll & Rooney PC(57) **CLAIM**

The ornamental design for a colonial base cap, as shown and described.

DESCRIPTION

FIG. 1 is a front perspective view of our colonial base cap; FIG. 2 is a left side view thereof, the right side view being a mirror image thereof;

FIG. 3 is a top view thereof;

FIG. 4 is a bottom view thereof; and

FIG. 5 is a front view thereof; and,

FIG. 6 is a rear view thereof.

In the drawings the colonial base cap is fragmented to indicate indeterminate length.
